FLYING SHEAR

Alexander Borzym, Detroit, Mich., assignor to
The Yoder Company, Cleveland, Ohio, a cor-
poration of Ohio

Application February 9, 1934, Serial No. 710,430

20 Claims. (Cl. 164—49)

This invention relates to machine tools, and although particularly concerned with metal cutting devices of the class commonly termed "flying shears," the principles thereof will be seen to be equally applicable to devices of many varieties for performing operations of various sorts upon different materials. An important object of the invention is the provision of an improved machine of the class indicated, especially suitable for operating upon extruded rolling or mill products, in the present instance to enable their severance into desired lengths, while in motion and without delaying their traveling movement.

Simplification of such devices and conservation of the space occupied, as well as reduction of both first cost and operating expense comprise further important objects.

Another object is the incorporation in such a machine of a novel carriage and cutter head assembly and improved supporting and operating means therefor of stronger and simpler design affording easier accessibility to working parts and insuring more rapid and accurate action than those heretofore used.

A still further object is the provision in such a machine of novel latching and latch operating means, together with improved resetting means for the latch.

Still another object is the provision of improved controlling means for such machines.

Other objects and advantages will be apparent from the following description, wherein reference is made to the accompanying drawings illustrating preferred embodiments of my invention, and wherein

Figure 1 is a central vertical section of a machine incorporating the principles of this invention, taken substantially on the line 1—1 of Figure 2 and looking in the direction of the arrows;

Figure 2 is a front elevation of the machine.

Figure 3 is a rear elevation thereof.

Figure 4 is a top plan view thereof; and

Figure 5 is a detailed section taken substantially on the line 5—5 of Figure 2 and looking in the direction of the arrows.

Crankshaft mounting and driving springs

Referring now to the drawings: 10 indicates as an entirety the frame of my improved machine. 15 indicates a crankshaft journaled in bearing brackets 16—17—18 extending upwardly from a support 36 carried by the top of the frame. The ends of the crankshaft project from and overlie the sides of the frame, carrying upon their projecting extremities cranks 20—21, which are ar-

ranged at a slight angle one to another, so that when one is at its upper dead center the other is somewhat offset, for a purpose which will presently appear. The cranks are adapted to be acted upon by springs 25—26 arranged to apply powerful torque to the crankshaft to turn it through a partial revolution. One spring 26 is arranged below the crankshaft, and the other 25 above it. Spring 26 is sheathed in a tube 29 and is connected to the crankshaft through connecting rod 10 5 and pitman 31. The spring 26 is fitted over the connecting rod and arranged to act in compression by bearing downwardly against a spring abutment 34 carried by the lower end of the rod, and upwardly against a fixed abutment 35 carried by the frame and serving to support the sheathing tube 29. The abutment 35 is provided with a clearance aperture (undesignated) permitting lateral as well as slidable movement of the rod therein.

Spring 25, which acts cooperatively upon the other end of the crankshaft and tends to turn it in the same direction, is housed in a tubular casing 39, the upper portion 39' of which extends above the spring and is internally tapped at its upper end to receive a threaded bushing 41 carrying an adjustable abutment plug 41. At its lower end the spring 25 bears against and urges downwardly a piston-like thrust element 27, connected to crank 20 as by connecting rod 30. Element 27 20 is reciprocable in the main supporting body of the spring housing 39, which body is shown integrally carried by bearing bracket 16. As stated above, crank 20 is slightly offset in the direction of desired movement when the crank 21 is at its upper dead center, and this is the normal positioning of these parts when the machine is cocked and before the commencement of the operating cycle. Resultantly, the spring 25 exerts a starting torque upon the crankshaft even though the parts are at rest in the cocked position. The starting torque will be seen to be greater by reason of the shown arrangement of the spring 25, in which it exerts thrust upon the connecting rod 30, than it would be if the spring acted in tension 40 upon the rod. It will of course be obvious that other sources of or means of storing power might be substituted for the springs.

Carriage and cutter-head

Also carried by the support 36 is a carriage, generally designated 40, which is laterally movable in a path substantially parallel to that of the work 41 and mounted on toggle links 42—43—44—45. Each link is pivotally attached at its 55

lower extremity to the support 38, as by a pivot bolt 47, and at its upper end similarly pivotally attached to the carriage by a bolt as 57. As a result of this construction the carriage is maintained horizontal despite its movability substantially in the line of movement of the work. The carriage is urged in the direction in which the work travels by a spring 100 carried by an arm 102 projecting laterally and upwardly from the frame, and its movement is controlled by a blocking cam 105, the operation of which will presently be considered in greater detail, together, also, with further explanation of the carriage actuating means.

15 Vertically slideable in the carriage is a cutter head 50, which is movable up and down independently of the position and movement of the carriage. The cutter head is actuatable through connecting rods 52 articulated at their upper ends to a common cross pin 53 fixed in the head, and at their lower extremities to a throw 51 of crank shaft 15; which throw is disposed between the bearing brackets 17-18.

It will thus be seen that despite the lateral movability of the carriage 40 made possible by its mounting upon the links 42-43-44-45, the cutter head may at all times be reciprocated vertically by the crankshaft acting through connecting rods 52. The guide plates 55-56 carried by the carriage 40 are fitted over and form gibbs in which the side plates 54-57 of the cutter head are vertically slideable. Springs 25-26 tend to turn the crankshaft 15 in such manner as to pull down the cutter head to do the work of cutting.

35 A cutter in the form of a punch 75 is carried by the head and adapted to be forced through the work by such downward movement of the head. A die 77 is carried by the anvil portion 18 and vertically apertured to receive the punch as well as provided with a longitudinal channel 79 through which the work may travel while being supported or "backed up" by the die. The work, designated 41, is shown as constituting a 40 rolling mill product of channel form adapted to be fed through the die directly over the anvil or table portion 78 of the head. Pilot pins 110 project upwardly from the table and slidably interfit with bushings 111 carried by the head to guide the latter and maintain accurate alignment of the punch and die. The slugs punched from the work in severing it, fall through a slot 112 in the table into a trough 113 by means of which they may be conducted away from the machine 45 or to a suitable receptacle (not shown).

Latching means

To releasably hold the springs under compression, the cranks 20-21 at their highest normal 60 (starting) points, and the head 50 at its starting point, and the parts cocked in such position, latch mechanism is provided comprising a lever 63 pivoted on the frame as at 59 at one end, and at the other end pivoted to the pin 61 which also 65 serves to couple the rod 28 and the pitman 31. A nose portion 60 of the lever 63 projects beyond the pin to form a striker or retaining shoulder beneath which the latching dog 62 may engage 70 to hold the rod 28 elevated, thus also maintaining the thrust element 27 elevated, both springs compressed, and the other portions of the apparatus in the positions shown with the cutter head in the elevated or starting position.

The latching dog 62 is formed as the upper 75 arm of a bellcrank pivoted on the frame as upon

bolt 61. The lower arm of the bellcrank, designated 66, is swingable by means of a solenoid 65 acting through a continuation 69 of its armature 68. As best appears in Figure 2, a portion 69' of the continuation 69 may overhang the bellcrank arm 66 to permit positive actuation of the latter upon downward movement of the armature. Energization of the solenoid tends to draw down the armature and thus swing the dog 62 from beneath the striker 60, freeing the latter and permitting the springs to rock the crank-shaft and pull down the cutter head with a quick and powerful stroke. A spring 71 urges the bellcrank toward latched position, acting to throw the dog beneath the striker 60 as soon as the latter is raised sufficiently and the solenoid is deenergized. Spring 71 is fitted over a pull rod 73 pivotally connected to lower bellcrank arm 66 and bears upwardly against a stop nut 74 carried by the top of the rod and downwardly against a plate 82 which projects from the frame above the arm 66 and serves as an abutment also for a spring 72 which similarly but independently draws upwardly the armature 68 and connecting element 69 when the solenoid is deenergized. The separate spring is provided to create clearance between the head 69' of connecting element 69 and the end of the bellcrank arm 66 upon which it acts when both are fully elevated. Such clearance, designated 83, permits the armature 30 and connected parts to gather momentum before taking up the load, thus insuring more positive action and allowing use of a lighter solenoid. An adjustable stop 84, also carried by abutment plate 82, permits regulation of the rest position- 35 of the dog and bellcrank. It will be seen that when the parts are in cocked position, energizing the solenoid trips the dog and allows the head to descend, and when the cranks are again raised to place the head in starting position the dog once more latches the machine in 40 cocked position.

Cocking means

Power for resetting the cutter head is supplied by the motor 75 mounted on a lower shelf 76 of the frame and connectible to the crankshaft through gearing 77-78-79-80. The first mentioned gear pinion 77, is arranged upon the motor shaft, gears 78-79 are fast upon an idler shaft 81, while the final gear 80 of the train is loose on the crank-shaft 15 but connectible thereto by means of a 50 slidible toothed clutch element 85 splined on the shaft. Upon movement of the clutch element its teeth are engageable with and disengageable from a complementarily toothed face portion 86 fast upon the hub of gear 80. The clutch member 85 is shifted to fasten the gear to and release it from the crankshaft through the agency of a fixed roller 88 acting upon a cam 87 fast upon and 55 rotatable with the clutch element 85, (which of course rotates with the crankshaft). Compression springs 89 trapped in suitable (undesignated) recesses in the clutch element 85 urge the latter toward engaged position, reacting directly against the body of the clutch at one extremity and at the other against thrust pins 91 projecting into the recesses and carried by a collar 92 fast upon the crankshaft. Cam 87 and roller 88 are proportioned so that when the latter is fixed in its normal operating position, the cam moves clutch element 85 into engagement with clutch element 86 as the crankshaft reaches the position it occupies upon completion of the actuation of the head 50 by the springs 25, 26. During operation of the 70 75

machine the motor 75 runs constantly, so that the gear 80 is constantly driven. As a result of this arrangement, upon engagement of clutch 85-86, the motor takes up the drive and continues to turn the crankshaft in the same direction until the head again reaches the starting position shown in the drawings at which time the cam 87 again disengages the clutch 85, and the head is held in such position by the latching means previously described, which holds the crankshaft in the corresponding position by engagement of the latching dog 62 beneath the striker plate 60. The cycle is then of course ready to recommence.

In order to provide means for positively holding the clutch element 85 out of engagement with element 86 at desired times, the roller 88 is mounted upon a swingable arm 90, pivoted on top of the frame as upon pivot bolt 93. The handle 95 by which the lever may be swung also controls a detent 96 which cooperates with recesses 97 into which it is normally forced by a spring 98 to hold the arm and so the roller 88 in either of two positions, the detent being releasable from the recesses by pulling upon the handle to permit swinging the lever. One of the two positions to which the lever is adapted to be moved is the operative position above described, in which rotation of the cam 87 acts to move clutch element 85 into and out of engagement with element 86, while when the handle is in the other position the roller 88 is so far from clutch portion 86 that the clutch element 85 cannot engage it, even when the lowest portions of the cam are in engagement with the roller. By so temporarily preventing engagement of the clutch 85-86 upon starting the machine, the motor and driven parts may be allowed to gain full momentum before the load is applied to the motor, as a result of which a motor of less power may be used than would otherwise be possible, with resultant economy of first and operating costs.

A counterweight 120 is keyed to the shaft 15 between the collar 92 and bearing bracket 17, and serves as a power storing device. In order to minimize the tendency of its inertia to resist quick starting of the crankshaft under the influence of the springs upon the commencement of a cutting stroke, the weight is so positioned that when the head is in starting position, as when the machine is cocked, the weight is elevated but spaced from its upper dead center, lying on the side thereof toward which it moves upon starting.

Carriage control

It will be seen that the reciprocating and controlling means just described for the vertically slideable cutter head 50 do not interfere with lateral travel of the carriage 40 with the work. As previously stated, the entire carriage by which the cutter head is carried is urged in the direction in which the work travels by a spring 100, trapped in an aperture 101 in the top of the upwardly extending arm 102 carried by the frame 10. The spring reacts against a plunger 104 which in turn forces the carriage in the desired direction by direct engagement against an end thereof. Movement of the carriage under the influence of the spring 100 is controlled by the cam 105 mounted upon an arm 103 arranged similarly to the arm 102 and projecting from the opposite side of the frame. The cam blocks movement of the carriage by reason of the engagement therewith of a roller 107 fastened to the carriage as by means of an arm 108.

It is of course obvious that only while the cutter

or other tool is in engagement with the work is it necessary that the carriage travel therewith. The cam is accordingly so connected to the crank-shaft as to be driven thereby in one direction to permit the carriage to advance with the work as the crankshaft turns through the working portion of the stroke, that is, as the cutter head 50 moves downwardly from the starting position shown to the bottom of its stroke and again upwardly until clear of the work. The cam is of course so contoured as to permit movement of the carriage at the desired rate, conforming to the rate of travel of the work. As stated above, and as shown in the drawings, the crank throw 51 is only slightly above horizontal when the cutter head is fully raised, and is accordingly positioned considerably in advance of the cranks 20, 21. By virtue of this arrangement, the cutter head is moved downwardly to force the punch through the work and then again upwardly to free the punch from the work as the cranks move downwardly under the influence of the springs 25-26, during which time the carriage continues to move forwardly with the work, as above stated.

The controlling cam 105 is driven by the crank-shaft, being carried by a shaft 115 journaled at one end in arm 103 and at the other in a co-operating bracket 113. Beyond the latter bracket the adjacent end of the shaft projects, carrying crank 116 which is connected to crank 20 by a link 117.

Automatic control

Carried by the arm 103 is a bed 120 which projects laterally from the machine, forming a support upon which is slidably mounted the base plate 121 of a control unit. The unit may be fixed in any of various positions along the bed by bolts 122 having head portions 122' slidably engaging a T-shaped slot in the bed, while a key 123 carried by the base 121 also engages in the slot to provide an accurate pilot for the control unit, as best shown in Figure 5. A trigger plate 125 forming part of the control mechanism is carried by the unit in alignment with the path of travel of the work 41, and the control mechanism is so arranged that when plate 125 is impacted by the traveling work, and has been moved a predetermined distance thereby, the circuit to solenoid 65 is automatically closed to trip the shearing mechanism, in the manner previously described, and sever the work—without interrupting or interfering with the travel thereof.

The trigger plate 125 is carried by an arm 126 pivoted on the ends of and maintained in horizontal position by parallel cranks 127-128. Crank 127 is fast upon a shaft 129 transversely journaled in an upstanding column 121' carried by the base 121. Carried by the shaft and housed within the column is a slideable toothed clutch element 130 which may be of similar construction to clutch 85 previously described, and keyed to the shaft as by the key 131 and by pins 132 carried by a collar 133 fast upon the shaft and slidably projecting into the body of the clutch element. Springs 134 trapped in the apertures in the clutch body in which the pins are slideable, urge the clutch to the right as viewed in Figure 5, tending to force its toothed end 136 into engagement with a cooperating clutch element 135 carried by and fast upon the hub of a worm gear 137. Gear 137 is normally loose upon shaft 129 and constantly driven by a worm 138 fast upon the driving shaft 139, to which is connected a motor 140 also supported by the base 121, as upon table 75

141. Fast upon the outside of the clutch body 130 is a cam ring 143 which in turning with the clutch body controllingly slides the same into and out of engagement with the clutch portion 5 135. Such sliding of the clutch is effected by engagement of the cam with a fixed pin 144 carried by the housing and projecting into engagement with one side of the cam. The cam is held in engagement with the pin by the springs 134, and 10 is so designed that at desired angular positions the clutch is free to move far enough to the right under the influence of the springs to allow engagement of its portion 136 with clutch element 135, thereby establishing a driving connection between 15 the gear 137 and shaft 129, the latter then being driven by the motor until the cam reaches another angular position at which it disengages the clutch element 130 from element 135, whereupon the motor ceases to drive the shaft. The 20 phases of the machine's operation at which such clutch movements take place to establish and break the driving connection between the motor and shaft 129 will subsequently be explained.

Carried by the opposite projecting end of shaft 25 129 to that carrying crank 127 is a plate cam 145, the contour of which is best shown in Figure 3. Cam 145 controls movement of a contact arm 147 carrying a movable contact point 138 which, under cam induced movement of the arm 147, is 30 movable into and out of engagement with a fixed contact 149. Contacts 148 and 149 are connected in series with the electrical circuit of solenoid 65, as by means of wires 151. A spring 150 bears downwardly upon contact arm 147 to insure good 35 contact by forcing the points 148—149 firmly together, and a cam follower 155 projecting from the under side of the contact arm and engageable by the high portions of the cam controls movement of the arm to make and break contact between the 40 points. Contact arm 147 is pivotally supported by the upper end of a post 152 rigidly upstanding from the baseplate between the motor and column 121', and which also carries a stub shaft 153 to which crank 128 is attached. Shaft 153 projects 45 through and from the other side of post 152 and carries upon its such projecting extremity a crank plate 154 lying substantially in a common plane with plate cam 145 and coupled thereto by a link 156, the points of connection of which are angularly spaced from those of bar 126 with cranks 50 127—128.

The adjustment of cams 143—145 is such that when crank arms 127—128 hang down substantially vertically and the trigger plate 125 is in its 55 normal rest position, clutch 130 is disengaged and gear 137 accordingly turns freely on shaft 129, the other working parts of the control unit remaining at rest. During the initial movement of the trigger plate and consequently of cam 145 60 under the influence of the work, cam follower 155 drops into a low portion 156 of cam 145, permitting the contacts 148—149 to close. Solenoid 65 is thereby energized and trips the latch 60—62, the machine quickly severs the work in the manner above described, and the severed section falls away and/or is removed in any desired manner (not shown). The work continues to advance somewhat after the closing of contacts 147—148 65 and before the complete severances of the work. 70 Such continued movement of the work forces back arm 127 a slight additional distance, and so turns cam 143 sufficiently to allow clutches 130—135 to engage. The motor 140 then takes up the drive and continues to turn the shaft and 75 connected elements, including cam 145, in the

same direction. As shown in the drawings, the low portion 156 of cam 145 is relatively short, and the dwell during which the contacts are held disengaged relatively long. Therefore as the motor 140 takes up the drive, which occurs shortly after energization of the solenoid, the contacts are again quickly separated and held so. When the parts again reach the position shown in Figures 2 and 3, cam 143 (Figure 5) again disconnects clutch elements 130—135, and the drive ceases, 10 leaving the contacts 148—149 still separated and the follower 155 substantially at the point shown in Figures 2 and 3, that is, near the end of the dwell and ready to drop off into the low portion 156 of the cam and close the circuit to the solenoid as soon as the cam 145 is rotated through a slight additional angle by impact of the work against the trigger plate.

It is only necessary to so position the control unit upon the bed 120 that the trigger plate 125 20 is impacted when the work has projected itself a desired distance beyond the cutter to provide for uniformly cutting the work into desired lengths.

While it will be apparent that the illustrated 25 embodiments of my invention herein disclosed are well calculated to adequately fulfill the objects and advantages primarily stated, it is to be understood that the invention is susceptible to variation, modification and change within the 30 spirit and scope of the subjoined claims.

What I claim is:

1. In a device of the character described, a frame, a traveling carriage carried thereby, a cutting element carried by the carriage and movable toward and from the same, an actuating member carried by the frame, means connecting said actuating member and cutting element for operating the latter, means for applying power to the actuating member to move it and the 40 cutting element from its initial position through a desired working phase, means operated by said actuating member for controlling the movement of the carriage relative to the movement of the cutter, releasable means operable to lock said power means in set position with said actuating member in its initial position, resetting means operable independently of said member and element, and means for connecting the resetting means to the actuating member to reset said 45 power means and locked by said releasable means. 50

2. In a device of the character described, a frame, a traveling carriage supported by the frame, a work-engaging portion carried by the carriage, a cutting element movable toward and from said work-engaging portion and also movable with the carriage, means including an actuating member for moving the cutting element toward and from the work-engaging portion, intermittently applicable power means normally 60 connected to the actuating member for moving it through a portion of its cycle of movement, additional power means normally disconnected from the actuating member for moving the actuating member through the remaining portion of 65 its cycle to re-set said first mentioned power means, clutching means for connecting said second mentioned power means and the actuating member at the end of the movement of the latter by said first mentioned power means, and 70 means responsive to the position of the actuating member for actuating said clutching means.

3. In a machine tool of flying construction, a frame, a carriage supported by but laterally movable relatively to the frame, a work-engaging 75

- portion carried by the carriage, a tool head also supported by the carriage and movable toward and from the work-engaging portion, a spring normally tending to move the carriage laterally 5 with the work, actuating means, including a driving member, carried by said frame for moving the tool head toward and from the work-engaging portion, and means operated by said driving member and including a cam for coordinating 10 the movement of the carriage under the influence of said spring with the movement of said tool head.
4. In a machine tool of flying construction, a frame, a carriage supported by but laterally movable relatively to the frame, a work-engaging portion carried by the carriage, a tool head also supported by the carriage and movable toward and from the work-engaging portion, actuating means for moving the carriage laterally, actuating 15 means for moving the tool head toward and from the work-engaging portion, including a driving member carried by the frame, means also carried by the frame operable for actuating the driving member through a portion of its movement 20 but inoperable through the other portion of its movement, means for actuating said driving member through said other portion of its movement, and controlling means for said last named means.
- 30 5. In a machine tool of flying construction, a frame, a carriage movable relatively to the frame, a work supporting portion movable with the carriage, a tool head movable toward and from the work supporting portion, and actuating means 35 mounted directly on the frame and connected to said head for moving the latter toward the work supporting portion independently of the position or movement of the carriage, said means including a spring, and resetting means independent of 40 said actuating means for moving said head to a desired starting position.
6. In a machine tool of flying construction, a frame, a carriage movable relatively to the frame, a work supporting portion movable with the carriage, a tool head movable toward and from the 45 work supporting portion, and means carried by said frame for actuating said head, including a device connected to said head, means operated by said device for controlling the movement of said carriage in relation to the movement of said head, a spring operatively connected to said device for moving it through a portion of its cycle of movement and power means normally disconnected from said device but operable intermittently for 50 connection thereto and move it through the remaining portions of its cycle whereby said spring is re-set.
7. In a machine tool of flying construction, a frame, a carriage movable relatively to the 55 frame, a work supporting portion movable with the carriage, a tool head movable toward and from the work supporting portion, means for moving the carriage, means for actuating the head including a device connected thereto, and a spring operatively connected to the device for moving it through a portion of its cycle of movement and power means, normally disconnected from said device but operable intermittently to be connected thereto and move it through the 60 remaining portion of its cycle whereby said spring is re-set, and means co-ordinated with the movement of the head for controlling movement of the carriage.
8. In a machine tool, a work supporting portion, a tool head movable toward and from said 65
- work supporting portion from a starting position through a work performing cycle, driving means for the tool head including a substantially horizontal shaft connected thereto, means for driving the shaft, and means for controlling movement of the shaft including a weight connected to the shaft and lying preponderantly on one side thereof and so arranged upon the shaft that when the head is in starting position the weight is elevated but is in advance of its upper dead center 10 in the direction of movement of the shaft.
9. In a machine tool of flying construction, a frame, a carriage movable relatively to the frame, a work supporting portion movable with the carriage, a tool head movable toward and from the 15 work supporting portion, and means for actuating the head including a crank connected thereto, spring means arranged to exert effort in one dimension and connected to the crank to apply power thereto through substantially half a revolution, the last mentioned connection of the spring to the crank being angularly spaced from the first mentioned connection, whereby the head may be moved both toward and from the work supporting portion during a half revolution of 20 the crank induced by the spring.
10. In a machine tool of flying construction, a frame, a carriage movable relatively to the frame, a work supporting portion movable with the carriage, a tool head movable toward and from the 30 work supporting portion, and means carried by said frame for actuating the head including a shaft and a crank connected thereto, spring means arranged to exert effort in one direction and connected to the crank to apply power to the 35 shaft through substantially half a revolution, to thereby move the head from a starting position toward the work supporting portion and again away therefrom, independent driving means normally disconnected from said shaft for returning the same to starting position, and clutching means responsive to changes of angular position of the shaft for connecting and disconnecting said independent driving means with respect to the shaft.
11. In a machine of the character described, a working head, driving means for the head including a shaft and power storing means connected thereto, latching means for holding the shaft in desired initial position, tripping means 45 for releasing the latching means to permit movement of the head under the influence of the power storing means, and independent driving means for said shaft normally disconnected therefrom and co-ordinated with the movement of the head 50 for rotating said shaft and returning the latter to said initial position.
12. In a machine of the character described, a work supporting portion, a working head movable toward and from the same, driving means 60 for the head, means for holding said driving means inoperative, electrically operable tripping means for releasing said holding means, and control means responsive to movement of work being operated upon for controlling said tripping 65 means, said control means including a trigger member appurtenant said work supporting portion, a cam connected to said trigger, contacts operable by said cam and electrically connected to said tripping means, and means for resetting said 70 cam after actuation thereof by the work including a motor connectible to said cam, and means responsive to the position of the cam for connecting and disconnecting said cam and motor.
13. In a shearing mechanism, the combina- 75

tion with a support, of a reciprocatable cutter mounted thereon, a shaft, operative connections between said shaft and said cutter, power means adapted to be set in condition for applying power to said shaft and operable when released for rotating said shaft through a portion of its cycle to effect operation of said cutter, separate power means for rotating the shaft through the remaining portion of its cycle and re-setting said first mentioned power means, control means between said shaft and said separate power means, co-ordinated with the rotation of the shaft under the influence of said first mentioned power means, for connecting said separate power means to the shaft and disconnecting said means therefrom, means for locking said first mentioned power means in re-set condition against operation, and means for actuating that element of said locking means which permits operation of said first mentioned power means after said separate power means has been disconnected from said shaft.

14. In a mechanism for shearing material, the combination with a support, of a reciprocatable cutter mounted thereon, a shaft, operative connections between said shaft and said cutter, power means adapted to be set in condition for applying power to said shaft and operable when released for rotating said shaft through a portion of its cycle to effect operation of said cutter, separate power means for rotating the shaft through the remaining portion of its cycle and re-setting said first mentioned power means, control means between said shaft and said separate power means, co-ordinated with the rotation of the shaft under the influence of said first mentioned power means, for connecting said separate power means to the shaft and disconnecting said means therefrom, means for locking said first mentioned power means in re-set condition against operation, and means controlled by the material for actuating that element of said locking means which permits operation of said first mentioned power means after said separate power means has been disconnected from said shaft.

15. In a mechanism for shearing material, the combination with a support, of a reciprocatable carriage thereon, a reciprocatable cutter mounted on said carriage, a shaft, operative connections between said shaft and said cutter, power means arranged to be set and locked in effective relation to said shaft, for rotating said shaft through a portion of its cycle to effect operation of said cutter, separate power means for rotating the shaft through the remaining portion of its cycle and re-setting said first mentioned power means, control means between said shaft and said separate power means, co-ordinated with the rotation of the shaft under the influence of said first mentioned power means, for connecting said separate power means to the shaft and disconnecting said means therefrom, means for locking said first mentioned power means in re-set condition against operation after said separate power means has been disconnected from said shaft, means for actuating said locking means, and mechanism, including means operated by said shaft, for reciprocating said carriage whereby it moves in one direction with the material.

16. In a shearing mechanism, the combination with a support, of a reciprocatable carriage thereon, a reciprocatable cutter mounted on the carriage, a crank shaft, operative connections between said shaft and said cutter, power means

adapted to be set in condition for applying power to said shaft and operable when released for rotating said shaft through a portion of its cycle to effect operation of said cutter, separate power means arranged to be connected to said shaft at the end of that portion of its cycle under the influence of said first mentioned power means, for rotating the shaft through the remaining portion of its cycle and resetting said first mentioned power means, control means co-ordinated with the rotation of said shaft in each cycle thereof for connecting said last mentioned power means to said shaft and disconnecting said means therefrom, means for locking said shaft against operation under the influence of said first mentioned power means following the resetting thereof, and means for actuating that element of said locking means which permits operation of said first mentioned power means after said separate power means has been disconnected from said shaft, and means actuated by said shaft for controlling the movement of the carriage with the material.

17. In a mechanism for shearing material, the combination with a support, of a cutter reciprocably mounted thereon, a shaft, operative connections between said shaft and cutter, locking means having an element normally disposed in locking position, power means arranged to be set in effective relation to said shaft when locked by said locking means and operable, when released, to rotate said shaft through a portion of its cycle to actuate said cutter, means controlled by the material for operating said locking means to permit operation of said power means, separate power means normally disconnected from but arranged to be connected to said shaft at the end of the movement thereof under the influence of said first mentioned power means for rotating said shaft through the remaining portion of its cycle for re-setting said power means, and means controlled by said shaft in co-ordinated relation to the movement thereof by said first mentioned power means for connecting said separate power means to said shaft and disconnecting said means therefrom.

18. In a mechanism for shearing material, the combination with a support, of a power element, a tool connected to and operated by said element, expansion means connected to said element and arranged to move it from its initial position substantially a predetermined distance, whereby said tool is actuated, separate means normally disconnected from said element, but arranged to be connected thereto for moving said element to its initial position and re-setting said expansion means, means for controlling the connection of said second moving means to said element and disconnection therefrom, and means for controlling said expansion means.

19. In a device of the character described, a frame, a traveling carriage carried thereby, a work-supporting portion carried by the carriage, a cutting element movable toward and from said work-supporting portion and also movable with the carriage, means including an actuating member for moving the cutting element toward and from the work-supporting portion, power means normally connected to the actuating member for moving it through a portion of its cycle of movement, separately operable power means for moving said member through the remaining portion of its cycle, said separately operable power means being disconnected from said member during movement of the latter by said first mentioned power means.

20. In a device of the character described, a frame, a reciprocable carriage mounted on the frame, a work bed movable with the carriage, a tool head mounted on said carriage and movable toward and from the bed, means carried by the frame and including a shaft for moving the tool head toward said bed, continuously operated means normally disconnected from said shaft but arranged to be connected thereto for moving the tool head away from the bed, means controlled by

said shaft for reciprocating said carriage during the active and receding strokes of said tool head and arranged to move the work bed and tool head with the work in the active stroke of the latter, releasable clutch means for connecting the shaft to said continuously operated means, and means co-ordinated with the movement of said tool head to predetermined positions for actuating said clutch means. 5
